UNITED STATES PATENT OFFICE.

CHARLES BARNES, OF DAYTON, KENTUCKY.

AUTOMATIC FIRE-EXTINGUISHER.

SPECIFICATION forming part of Letters Patent No. 324,977, dated August 25, 1885.

Application filed June 13, 1885. (No model.)

To all whom it may concern:

Be it known that I, CHARLES BARNES, a citizen of the United States, and a resident of Dayton, in the county of Campbell and State 5 of Kentucky, have invented certain new and useful Improvements in Automatic Fire-Extinguishers, of which the following is a specification.

My invention is an improved distributor for 10 automatic fire extinguishers. Its object is an inexpensive device that requires but little skill in fitting the parts together, and while being more sensitive to heat than those in common use is not liable to be released accidentally or by any pressure brought to bear 15 upon its valve until the temperature of the room or other position where it is placed is raised to a certain degree by heat occasioned by fire, and when the temperature is raised 20 will be certain in its action.

The invention will be first fully described in connection with the accompanying drawings, and its novel features particularly pointed out and referred to in the claims.

25 In the accompanying drawings, in which like parts are represented by similar reference-letters wherever they occur throughout the various views, Figure 1 is a side elevation of my improved distributor held in the closed 30 position. Fig. 2 is a vertical central section of the same. Fig. 3 represents in side elevation the several parts of the distributor detached from each other. Fig. 4 is an elevation of the same, looking down upon the top.

35 The frame A, within and upon which the operative parts of the distributor are mounted, consists of a light metal casting. It has a ring, a, which has an interior screw-thread to receive the tube B. This tube has, about its 40 mid-length, an angular wrench-seat, b. The portions upon each side of the wrench-seat are externally screw-threaded. The screw-threaded portion upon one side secures the tube to the frame A, and the screw-threaded portion on the opposite side of the wrench-seat b is for attaching the distributor to the end of the discharge pipe. The valve fits within the end of the pipe B. Within the frame A the inner edge is beveled to form a seat for the 45 conical valve c. The straight portion c' fits the inner bore of tube B as a piston. The valve-stem c² passes into a perforated boss, a',

in the upper portion of the frame A, and the valve is held to its seat firmly by a set-screw, d, which passes through a boss in the releasing device D. This releasing-lever has a detent, d', to engage under a hook, a², and it has also lugs d² projecting down from the opposite end at each side to straddle the arm a³ of the frame A. The lugs d² are perforated to receive a fusible pin, e, which passes through the lugs and under the hooked end of the arm a³. The piece D has also lugs d³, which pass upon each side of the frame A to steady the piece D in position.

60 The distributor C, which is cast in the same piece with the valve and valve-stem, is dished out on the under side, leaving a flaring rim or flange that spreads the water in a thin sheet when the valve is released from its seat and thrown by the force of the water up against the upper arm of the frame A. The upper side of this distributor C is also concave from the rim into the valve-stem c², for the purpose of lightness. It will be noticed that the portion of the valve-stem nearest the distributor is enlarged to stop against the upper arm of the frame when the valve is thrown open, and in some cases the under side of the distributor is made with eccentric flanges, so that the 70 force of the water will give it a rotary motion, the valve-stem serving as the axis on which it rotates.

65 In fitting the valve together it is only necessary to first insert the valve-stem c² through the boss a', then secure the piece B into the ring a, place the piece D in position on the frame, as shown in Figs. 1 and 2, pass the fusible pin e through the openings in the lugs d², and tighten the valve to its seat by 80 means of the set-screw d. It will be seen that the fusible pin, or at least the portion of it that passes under the hooked end of arm a³, is entirely exposed, so that it will be readily melted in case of fire. When it is 85 melted, the force of the water passing through the pipe B will throw the valve from its seat; but by reason of the straight or piston part c' no water will be discharged until the portion c' of the valve leaves the pipe B. By this time 90 the arm D is thrown entirely from the frame A, so that there is no danger of the water striking the fusible pin and preventing the 95 complete opening of the valve.

It is evident that the set-screw d may be dispensed with and the valve-stem made to bear directly upon the arm D . In this case the portion of the tube above the wrench-seat or the valve-stem should be made longer than shown, so that the valve-seat can be tightened up against the valve, instead of tightening the valve down upon its seat by the set-screw; but I prefer the form shown, as the parts can be more conveniently secured together, and by the thumb-screw d the valve can be securely seated without danger of subjecting the pin e to unnecessary strain.

It would be an inferior modification of my invention to widen the end of the arm a^3 and perforate it, so that the pin e would pass through the lugs d^2 and this perforation, or to unite the ends of arm a^3 and the adjacent end of the releasing device D by a fusible solder-joint.

When the fusible connection is released by heat, the distributor C is thrown and held against the upper cross-bar of the frame A by the force of the water discharged through tube B .

B. It is therefore evident the full effect of the distributor in use would be attained if it

were cast as a part of the frame and vertically above the discharge-opening and the valve-stem c^2 made to slide through it; but it would be more expensive to make it this way. 30

What I claim is—

1. In an automatic fire-extinguisher, the combination of the frame A , having ring a , perforated boss a' , hook a^2 , and arm a^3 , the screw-threaded tube B , secured in the ring a 35 of the said frame, the valve, and distributor C , adapted to slide within said frame and close the end of tube B , and the releasing device D , having its short arm loosely coupled to said frame and its longer arm coupled to the end 40 of the arm a^3 by fusible material to hold said valve to its seat until released by heat, substantially as shown and described.

2. In an automatic fire-extinguisher, the combination, substantially as set forth, of 45 tube B , having seat b , the frame A a a' a^2 a^3 , and releasing device D d d' d^2 with the valve and distributor C c c' c^2 , and fusible pin e .

CHARLES BARNES.
